his Attorney.

UNITED STATES PATENT OFFICE.

SIMON RUDOLPH OPPENHEIM, OF KEELER, CALIFORNIA.

KELP-DRIER.

1,266,041.

Specification of Letters Patent. Patented May 14, 1918.

Application filed June 7, 1917. Serial No. 173,363.

To all whom it may concern:

Be it known that I, SIMON RUDOLPH OPPENHEIM, a citizen of the United States, residing at Keeler, in the county of Inyo and 5 State of California, have invented a new and useful Kelp-Drier, of which the following is a specification.

This invention relates to means for drying kelp before burning in an incinerator, and 10 particularly to that type of such drying means, in which the kelp is pressed through a rotating drum, through which a current of hot furnace gases or hot air is also passed.

The main object of the present invention 15 is to provide a rotating drier of this type, in which a very efficient drying of the kelp is obtained.

Another object of this invention is to prevent excessive heating of the drum itself, so 20 that no insulating covering is required.

Another object is to provide for uniform 25 progress of the kelp through the drum.

Another object is to prevent the kelp from 30 rolling back out of the drum after it has been fed into it.

The accompanying drawings illustrate an 35 embodiment of my invention and referring thereto:—

Figure 1 is a side elevation of the rotating 40 drier.

Fig. 2 is a vertical section of the same.

Fig. 3 is a section on line 3—3 in Fig. 2.

Fig. 4 is a side elevation of one of the 45 transverse plates in the part of the drum through which the kelp first passes.

Fig. 5 is a side elevation of one of the transverse plates in the latter part of the 50 drum.

The apparatus comprises a hollow drum 40 1, mounted to rotate on bearings 2 at one end and provided with gear means 3 at the other end to effect rotation of said drum in the direction indicated by the arrow in Fig. 3. The material is fed into the drum at one 45 end, for example by a chute 4, and hot gases are also introduced at this end, for example from a furnace whose outlet is indicated at 5. The other end of the drum may discharge the hot gases into any suitable flue or 50 stack.

A plurality of longitudinal vanes 6 extend throughout the length of the drum, these 55 vanes being inclined so that their inner ends are advanced in the direction of rotation, so as to form pockets 7 which receive the kelp and carry it well toward the top of the

drum at each revolution, before allowing it to fall to the bottom of the drum.

The vanes 6 are preferably provided with 60 portions 9 extending obliquely of the length of the drum at the entering end thereof so as to positively retain the material deposited from the chute 4. If desired, these oblique portions may be cut away at the ends as at 65 10 to permit them to pass by the delivery chute.

The motion of the kelp along the drum is 70 accomplished by means of transverse plates 12 and 13 extending between the vanes 6. These plates are placed at intervals throughout the portion of the drum in which the vanes 6 extend longitudinally and are arranged in a spiral series so as to form a sort of screw conveyer for the kelp as the barrel rotates, the pitch of these plates being such 75 as to produce the required velocity of passage of kelp through drum.

The transverse plates 12 near the entering 80 end of the drum preferably fit fairly tightly against the wall of the drum, and may be provided with perforations 14 to permit passage of hot air or gas through the kelp while in the pockets 7, so that such hot air or gas may have access to all of the kelp in the drum at all times.

The transverse plates 13 toward the discharge end of the drum may, however, be straight at their outer edges which permits effective access of hot air without any perforations and these plates may therefore be 85 imperforate as shown.

The plates 12 and 13 also serve to support 90 the vanes 6, but if desired, auxiliary spacing and supporting strips 16 may be placed connecting said vanes at intervals. Said 95 plates are preferably of less height than said vanes so that they occupy peripheral portion of the pockets formed by said vanes, whereby the vanes are enabled to have a more effective lifting action in the kelp. 100

The operation of the above-described apparatus is as follows:—

The drum 1 is rotated at a speed such 105 that the kelp will be thoroughly dried before leaving the same, it being seen from the above description that with transverse plates having a given pitch, the rate at which the kelp is fed through the drum depends on the velocity at which the drum is rotated, while the quantity of material 110 fed through the drum in a given time depends upon this velocity and also upon the

rate at which kelp is fed into the drum. These factors may be readily determined by experience.

5 Wet kelp is fed into the drum from the chute 4, while a current of hot air is admitted from the furnace outlet 5 and passes throughout the length of the drum. The kelp is fed by the oblique vane portions 9 into the first row of pockets 7, which lift 10 it toward the top of the drum and then permit it to fall through the hot air current to the bottom of the drum, this operation being continually repeated until the kelp reaches the other end of the drum. The kelp is thus 15 repeatedly separated and every part of it subjected to the drying action of the hot air at the delivery end of the drum. The dried kelp may be discharged into any suitable receiving means.

20 What I claim is:

1. A drier for kelp and like material comprising a cylindrical rotatably mounted drum, having internal vanes extending obliquely from the feed end of the drum part 25 way along the drum, and thence longitudinally along the drum, parallel to the axis of the drum, to the delivery end of the drum, said vanes being directed so that their inner

ends are advanced in the direction of rotation to form lifting pockets, and cross plates 30 extending between said longitudinally extending vanes and extending obliquely with reference to the longitudinal direction so as to move the material longitudinally of the drum.

2. A drier for kelp and like material comprising a cylindrical rotatably mounted drum, having internal vanes extending obliquely from the feed end of the drum part 35 way along the drum, and thence longitudinally along the drum, parallel to the axis of the drum, to the delivery end of the drum, said vanes being directed so that their inner ends are advanced in the direction of rotation 40 to form lifting pockets, and cross plates 45 extending between said longitudinally extending vanes and extending obliquely with reference to the longitudinal direction so as to move the material longitudinally of the drum and said plates being of less height 50 than said vanes so as to occupy only the peripheral portions of said pockets.

In testimony whereof I have hereunto set my hand, at Keeler, California, this 21st day of May, 1917.

SIMON RUDOLPH OPPENHEIM.
